UNITED STATES PATENT OFFICE.

WILLIAM JAMES FOURACRE AND ALLAN FOURACRE, OF HARDEN, NEAR BINGLEY, ENGLAND.

DEVICE FOR INDICATING SPRING PRESSURE UPON SPINNING-MACHINE ROLLERS.

Application filed August 29, 1924. Serial No. 734,915.

To all whom it may concern:

Be it known that we, WILLIAM JAMES FOURACRE and ALLAN FOURACRE, subjects of the King of Great Britain, and residents of Long Lane (no number), Harden, near Bingley, in the county of York, England, have invented a certain new and useful Device for Indicating Spring Pressure Upon Spinning-Machine Rollers, of which the following description, having reference to the accompanying sheets of drawings, is a specification.

In connection with certain rollers in spinning machines used in the production of yarns or threads of fibrous substances the pressure of one roller against the other is brought about by an adjustable spring and since a considerable number of said pairs of rollers are made use of in each machine it is of importance that the pressure exerted by the spring in each case should be even throughout the whole series otherwise the gripping actions of one pair of rollers are different to those of another pair and bring about undesirable results. The springs made use of are of the open spiral type and are screwed down by operating screws as the attendant from time to time thinks fit and as hitherto no indication has been provided for showing the positions in which the springs are adjusted, the attendant has had to adjust said springs empirically thus some of the springs are made to exert extreme pressure while other springs are not nearly so much under compression. Our invention consists in the production of indicating devices whereby the amount of compression that the springs have undergone or to which they are regulated, may be indicated so that all the springs may be compressed to the same extent which is shown by the devices we employ, thus obtaining as nearly as possible, uniformity of pressure throughout the whole arrangement whether said springs are for the drawing rollers of spinning or like machines or for other purposes in connection with the same type of apparatus.

In order that our said invention may be readily understood we have hereunto appended sheets of drawings illustrative thereof to which by figures and letters reference is made in the following description.

Fig. 1 is an end view of the shafts and of two rollers (which have to be forced into contact with each other in known manner)

showing the application thereto of our improved devices.

Fig. 2 is a similar view to Fig. 1 but illustrates a modification hereinafter explained.

Fig. 3 is a view of the parts shown by Fig. 1 as seen in the direction looking from right to left of said figure.

Fig. 4 is a similar view to Fig. 3 but shows the parts illustrated by Fig. 2.

Fig. 5 is a side elevation of our improved devices drawn to an enlarged scale.

Fig. 6 is an elevation of the parts shown by Fig. 5 as seen in a direction looking from left to right of said figure.

Fig. 7 is an elevation of parts shown by Figs. 2 and 4 respectively the same being drawn to an enlarged scale.

Fig. 8 is a sectional elevation of our improved parts of the modified form shown by Figs. 2, 4 and 7.

In the drawings annexed hereto the rollers 3 and 4 are the ordinary delivery rollers of a spinning machine. The series of lower rollers 3 are fixed upon a horizontal shaft 3^a which extends lengthwise the machine and is rotated in the usual manner while the upper series of rollers 4 are arranged in pairs as shown by Figs. 3 and 4 so that the shafts 4^a of said pairs of rollers 4 may be engaged with by a hook 14 which slides over the screw 5 having a hook 5^a at its lower end. This hook 5^a engages with a bracket 15 fixed on the framework of the spinning machine so that the upper rollers 4 may be forced into contact with the lower rollers 3. The said arrangement of devices is of the ordinary character used in all worsted and like spinning machines.

In carrying our invention into effect we arrange the pressure springs 2 for the series of drawing and delivery rollers 3 and 4 of a spinning frame to be all of the same strength and length in order that when mounted upon their respective screws 5 any alteration in the compression of any of the said springs 2 may be shown by an indicator. This indicator according to one arrangement consists of a bent arm 6 which is mounted upon the screw 5 prior to the placing thereon of the spring 2 and which is arranged to have graduations *a*, see Figs. 3 to 6 (which may be numbered if desired) in order to show the space or distance through which any spring 2 may have been

compressed by its adjusting nut 7 acting upon it when screwed down over its screw 5.

This indication is given by the nut 7 compressing the spring 2 and at the same time forcing an arm 8 down over the indicating plate 6 so that the space that it has been forced over said indicating plate 6 is shown by the markings *a* formed on said plate. The arm 8 is slotted to take over the indicating plate 6 so that it is thereby kept in proper relationship therewith.

As an alternative formation to the plate 6 and arm 8, we have a hollow sleeve 6^a and bush 8^a taking into same as shown by Figs. 2, 4, 7 and 8.

The actions of these latter parts are identical with those of the former except that the markings *a* are now shown at *a*¹ on the bush 8^a instead of being shown on the part 6 in the other arrangement as it is obvious that the same indicating feature is secured by screwing down the nut 7 over the screw 5 to cause the bush 8^a to descend into the sleeve 6^a so that markings *a*¹ on the outside thereof will indicate how far said bush has descended into the sleeve thus the amount that each spring 2 has been compressed is shown clearly by the markings *a*¹ on the bush 8^a the same as the compression of the spring is shown by the markings *a* on the plate 6.

Such being the nature and object of our said invention, what we claim is:—

1. In a spinning machine, the combination of a shaft, a roller supported by the shaft to rotate about the axis thereof, a second roller arranged to rotate in peripheral contact with the first said roller, a relatively stationary member having a threaded stem extending across the axis of the first said roller, a slide fitted on said stem and having a lateral projection extending across and bearing against the shaft supporting the first said roller, a coiled spring surrounding the stem and tending to move the slide to maintain contact between the rollers, a nut mounted on the stem and movable thereon

to vary the strength of the spring, and means for indicating the location of the nut on the stem in any adjusted position.

50

2. In a spinning machine, the combination of a shaft, a roller supported by the shaft to rotate about the axis thereof, a second roller arranged to rotate in peripheral contact with the first said roller below the horizontal plane of the shaft, a relatively stationary member having a threaded stem extending across the axis of the first said roller, a slide fitted on said stem and having a lateral projection extending over and bearing on the shaft, a coiled spring surrounding the threaded stem above and bearing on said slide, a nut engaging the threaded stem and movable thereon to vary the compression of the spring, and means for indicating the location of the nut on the stem in any adjusted position.

60

3. In a spinning machine, the combination of two shafts, a roller supported by each shaft to rotate about the axis thereof, said rollers being in peripheral contact, a relatively stationary member extending across the axis of one of said rollers, a slide mounted on said member and engaging one of said shafts, a sleeve surrounding said member beyond the slide, a coiled spring within the sleeve acting to move the slide to maintain contact between the rollers, a nut engaged with the stem, and a member interposed between the nut and spring and telescopically engaging the sleeve, one of said telescopic elements being provided with graduations cooperating with the other said element to indicate the extent of compression of the spring.

65

In testimony whereof we have signed our names to this specification in the presence of two subscribing witnesses.

WILLIAM JAMES FOURACRE
ALLAN FOURACRE.
